AIR CONDITIONING APPARATUS

Lester S. Keilholtz, Detroit, Mich., assignor, by
mesne assignments, to Borg-Warner Corpora-
tion, a corporation of Illinois

Application December 20, 1933, Serial No. 703,279

14 Claims. (Cl. 261—115)

This invention relates to humidifying and otherwise conditioning air or other similar normally non-condensing gases and has particular relation to small apparatus adapted for the conditioning of air in homes, the rooms of office buildings or other small enclosures where the proper conditioning of air is considered important.

An object of the invention is to provide a relatively small and semi-portable air cleaning, humidifying and circulating unit which is comparatively inexpensive in construction and which can be easily installed in buildings and rooms constructed originally without particular regard to the conditioning of the air therein, other than the normal provisions for ventilation through windows, etc., and for heating.

Another object of the invention is to provide an apparatus for conditioning a limited quantity of air to be forcibly discharged into a room or a plurality of interconnected rooms, not only to increase the humidity of all of the enclosed air by diffusion throughout, but to cause such a turbulent condition in the air that stratification of air at different temperatures throughout an enclosure will be greatly decreased.

Another object of the invention is to so construct and arrange the parts normally employed in an air conditioning apparatus as to permit the assembly of such parts in the minimum amount of space and to permit the construction of a cabinet having proportions which will be pleasing in appearance.

Another object of the invention is to provide an air conditioning apparatus capable of operating with substantially no audible noise and which is provided with sound deadening or absorbing material properly arranged therein for rendering less audible whatever noise may be created by the operation of the apparatus.

Another object of the invention is to provide an air conditioning apparatus in which a water spraying device is so arranged as to produce a spray, the film of which bursts at its edges into a finely atomized spray of water, through which the flow of air is directed for removing both soluble and insoluble dirt and soluble odors.

Another object of the invention is to provide an air conditioning apparatus consisting of a number of unitary and preferably separable parts which can be assembled and disassembled for service and adjustment without any very great amount of effort.

Another object of the invention is to provide in an air conditioning apparatus, a device for forming a finely atomized spray in a minimum of

enclosed space and in which the region of formation of the spray is located at least a predetermined minimum distance from that portion of the walls of the apparatus about the periphery of the spray so that a highly efficient atomization of the water occurs and the pressure thereof is largely spent before the water contacts the walls of the apparatus whereby a minimum of noise is produced.

The particular embodiment of the invention disclosed herein, for the purpose of illustration, consists generally of an inner casing and an outer casing, between which the air supplied to the apparatus is admitted and of which the outer casing is constructed and finished in such manner as to provide an attractive piece of furniture suitable for use in homes or elsewhere. The inner casing has a pair of openings in opposite sides thereof adjacent the top of the casing and through which air is admitted to a pair of centrifugal blowers arranged adjacent thereto immediately inside the casing. These blowers are arranged within a pair of blower housings which discharge downwardly into the main or lower part of the inner casing, and are secured for operation upon the opposite ends of a shaft extending transversely of the casing and driven by a motor which is resiliently mounted between the two blower housings.

Arranged just below the aforesaid outlet to the blower housings and slightly rearwardly therefrom is a water spraying device which is adapted to discharge a fine spray of water practically entirely across the casing beneath the blower housing outlets and in a general direction downwardly and forwardly from the region of location of the spraying device. The air discharged from the blower housing outlets is adapted to flow through the aforesaid water spray by passing downwardly into that portion thereof on one side of the region of location of the spraying device, and being reversed in its direction of flow by the curvature of the bottom of the casing, to flow upwardly through that portion of the spray on the opposite side of the region of location of the spraying device. Thereafter the moisture-laden air is discharged upwardly, from behind the blower casings, through an excess moisture eliminator and scrubber plates and thence outwardly through registering openings in both the inner and outer casings and in which is located a grille device for properly directing the blast of air discharged and for preventing any foreign objects from being inserted through the openings. In the

outlet from the inner casing, between the aforesaid grille and the eliminator and scrubber plates, is arranged a quantity of sound-absorbing or deadening material, which tends to reduce to an unobjectionable minimum whatever noise may be created inside the inner casing by the formation of the spray and the flow of air. Sound-absorbing material is also employed not only in the space between the walls of inner and outer casings to absorb any vibration in the material of which the casings are formed, but also to prevent, as far as possible, the transmission of sound between the casings from the inlets through which air is supplied to the two blowers.

The air inlets to the apparatus may be provided with suitable removable filters for precipitating the sooty, oily, sticky and relatively fine dirt usually entrained in air, prior to its entry into the inner casing, for preventing the deposit and accumulation of such dirt internally on the walls and parts of the apparatus.

For a better understanding of the invention, reference may be had to the accompanying drawings and in which:

Fig. 1 is a front elevational view of an air conditioning apparatus embracing the principles of the invention, and which is installed in a room of a building with a heating coil located in the furnace of the building for the purpose of supplying heated water to the apparatus;

Fig. 2 is an enlarged view of the apparatus with certain outer portions thereof broken away so that the interior structure can be seen;

Fig. 3 is a fragmentary sectional view of the apparatus taken substantially on line 3-3 of Fig. 2;

Fig. 4 is a longitudinal sectional view through the apparatus as the latter might appear substantially in the plane of line 4-4 of Fig. 2;

Fig. 5 is a fragmentary sectional view of the apparatus taken substantially in the plane of line 5-5 of Fig. 4;

Fig. 6 is a cross sectional view through the spraying device employed in the apparatus, and as the device might appear substantially in the plane of line 6-6 of Fig. 4;

Fig. 7 is a fragmentary cross sectional view through the apparatus substantially in the plane of line 7-7 of Fig. 4 and showing the blower casings and motor compartment arranged therein;

Figs. 8 and 9 are sectional views of the blower apparatus taken respectively on lines 8-8 and 9-9 of Fig. 7;

Fig. 10 is a fragmentary sectional view of the apparatus taken substantially in the plane of lines 10-10 of Fig. 4;

Fig. 11 illustrates a different form of discharge chamber which may be employed in the apparatus illustrated by the preceding figure;

Fig. 12 is a form of water heater which, if desired, may be employed in practicing the invention;

Fig. 13 illustrates a hot and cold water mixing valve preferably embraced in the apparatus and employed in the operation thereof; and

Figs. 14 and 15 are side and end elevational views, respectively, of a combined sound-absorbing box and filter, with which the apparatus may, if desired, be provided.

Referring particularly to Fig. 1, there is illustrated at 16, an air conditioning apparatus or unit supported on the floor 17 of a room of a building and provided with an electrical con-

ductor or supply cord 18 which is connected by a plug 19 to an electrical outlet 21 arranged in the building wall. As shown, the apparatus is supplied with cold water through a supply pipe 22 and with hot water through a supply pipe 23 in the latter of which a heater 24 located in the hot air space 26 of an air heating furnace 27 is arranged, although it will be apparent that other arrangements may be provided for supplying water to the unit at any desired temperature, 10 depending upon the extent of air humidification which it is desired to produce.

In order to be able to supply a variable mixture of either hot water or cold water or a mixture of both, there can be employed in the apparatus 15 (see Fig. 13), a water mixing valve indicated at 28 and to which the supply pipes 22 and 23 are attached. From this valve a mixture of hot and cold water in the desired proportions may be discharged through a supply pipe 29. In order 20 to be able to control the proportion of hot and cold water supplied by the pipe 29, there is provided for the valve 28, a control handle 31 which operates certain well known valve mechanism located inside the valve casing and adapted for 25 producing this result. From the pipe 29 water is supplied through a strainer 32 and a pipe 33 to a pressure reducing valve 34 which is provided with a manually adjustable control device 36 by which the pressure of water supplied to the 30 apparatus may be reduced to any desired extent. From the valve 34 the water is supplied at reduced pressure through a pipe 37 (to which a pressure gauge 38 may be attached) to the inner casing 39 of the apparatus through a pipe 41 35 secured thereto, and to a spray nozzle 42 supported upon the upper extremity of pipe 41.

While the spray nozzle or device 42 can be arranged in any desired position inside the casing 39, as illustrated, preferably it is set to discharge 40 a spray of water, the central axis of which is coincidental with the axis of the standpipe 41. The pipe 41, which is secured at its lower end in a flanged head 43 secured over an opening in the casing 39, comes through the casing substantially 45 midway between the two side walls thereof and forwardly of a median plane between the front and rear walls of the casing. From this location the pipe extends upwardly at such an angle as to locate the nozzle 42 disposed upon the upper 50 end thereof slightly to the rear of the aforesaid median plane and in such position as to discharge a spray forwardly and downwardly toward the bottom of the casing.

The nozzle 42 consists of a relatively small 55 supply casing 44 threaded upon the upper end of the pipe 41, and having a cavity 46 formed therein, the upper open end of which is covered by a frusto-conical shaped head member 47, the flanged edges 48 of which are secured rigidly to the casing 44 by a flanged nut 49 threaded around the outer upper extremity of the casing. In the central portion of the head member 47 there is formed a circular orifice 51 which is 60 adapted to discharge a small column of water, 65 at a pressure determined by the adjustment of the reducing valve 34, against the center of a concave or arcuate end portion 33 of a spray target or small rod 54. The arcuate end portion 53 is formed inwardly of the end of the target 54 70 in such manner as to reverse the direction of flow of the water column 52 to form a conical shaped water film 56 directed oppositely thereto. The target 54 is secured by a set screw 57 in an opening formed in a split end portion 58 of an arcu- 75

ate supporting arm 59, the opposite extremity of which is secured into and supported as is indicated at 61, by the casing 42.

The films 56, which is only partially shown in Fig. 6, tends to decrease rapidly in thickness toward the outer extremity thereof and bursts into a fine spray indicated generally at 62 when the surface tension of the liquid is increased beyond the point at which the liquid film can be maintained.

The target 54 is so spaced from the side walls of the casing 39 and arranged therein, that during operation of the apparatus the minimum distance from target 54 to where the spray 15 strikes the inner walls of the enclosing casing is such that a highly efficient atomization of the spray water is effected, and the pressure thereof is largely spent before contacting the walls of said casing 39, whereby a minimum of noise is 20 produced. The particular form of the spray as well as the location of the target are important factors in permitting such a highly efficient utilization of the available enclosed space within in the casing 39.

25 In order to carry away whatever water may collect upon the parts of the nozzle 42, there is provided a drip trough or drain member 63 which is secured to a lower portion of the support 59 in such position that its discharge end will release the water at a point closely adjacent the wall of the inner compartment 39 and thus eliminate any noise which might result from the falling of large drops of water.

The inner casing 39 is constructed principally 35 of a pair of end or side sections 64 and 66 having a relatively continuous sheet of metal 67 secured between the flanged edges thereof, to provide an arcuate upper section 68, a vertical front section 69, an arcuate or a substantially semi-cylindrical bottom section 71 and an upwardly extending rear section 72 terminating at its upper extremity at about the same level as the opposite end of the sheet to provide a discharge opening 73 from the casing interior.

45 The casing 39 is supported at opposite ends thereof upon a pair of supporting frames 74 and 76 secured to the casing in any suitable manner as by brackets 77. Secured in the upper front portion of the inner casing 39 just below the 50 arcuate upper section 68 of the casing and held removably in position therein by screws indicated at 78, is a frame 79 having a lower portion 81 and a back portion 82, the latter of which is spaced a substantial distance from the back portion 72 of the casing 39 in order to provide a passage 83 extending upwardly toward the outlet 73. Supported in spaced relation upon the frame 79, to provide an opening 84 therebetween and a pair of openings 86 and 87 adjacent the casing ends 64 and 66, is a pair of blower housings 88 and 89 having outlets 91 and 92, respectively, extending downwardly through the bottom portion 81 of the frame and into a region just above the spray 62 formed by the nozzle 42.

65 Covering the portion of the frame 79 between the blower housings 88 and 89 is a quantity of sound absorbing material 93 and above which is secured a motor 94 having supporting brackets 96 and 97 extending downwardly therefrom and the lower ends of which are secured to the frame 79 by bolts indicated at 98. The brackets 96 and 97 are secured to the motor 94 by supports 95 attached at the upper ends thereof by resilient bushings 90 and studs 85, to the motor casing. 70 Openings 99 formed in the adjacent ends of the

blower housings 88 and 89 are adapted to receive centrally thereof the opposite ends of a shaft 101 extending through the motor 94 and which support centrifugal blowers 102 and 103 fastened to the shaft ends within the housings by screws 104. 5 The electrical supply cord 18 which extends within the casing 39, provides electrical energy for operating the motor 94. The blowers 102 and 103, which are driven by the operation of the motor 94, are adapted to receive air adjacent the 10 axes of rotation thereof and to discharge such air at a substantial velocity from around the peripheries thereof.

While the blowers 102 and 103 may be of any preferred form, in the present instance they embody closed end walls 106 at the ends thereof adjacent the motor 94 and rings 107 adjacent the opposite ends thereof, through which the inlet air for the blowers is provided. Between the ends 106 and the rings 107 of each blower are secured 20 arcuate forward type blades 108 by which air is discharged outwardly at a substantial velocity.

Formed in the remote sides of each of the blower casings and directly opposite the blowers 102 and 103 located therein, are inlet openings 25 109 having annular spacing members 111 disposed therein which contact with the inner extremities of inlet ducts 112 secured by screws 113 in openings formed in the end walls 64 and 66.

The lower edges of the blower housing outlets 30 91 and 92 are inclined downwardly toward the front wall 69 of the casing 39 and in addition are provided with troughs or drains indicated at 114 which are employed for the purpose of draining 35 any water collecting upon the walls of the structure toward the casing front wall 69. Secured with the lower extremities thereof in the troughs 114 adjacent the side walls 64 and 66 and with the upper extremities thereof disposed against the walls, are inclined baffles 116 and 117, and likewise, there are employed between the casings inclined baffles 118 and 119 and the upper extremities of which are secured together at 120. These baffles tend to close up the space surrounding the outlets and provide means for conveying the water 40 collecting thereon into the troughs 114. The rear edges of the outlets 91 and 92 are inclined downwardly in opposite directions, as is indicated at 121 and 122, and such edges also are provided with troughs similar to the troughs 114 and the 50 opposite ends of which drain into the latter.

It will be apparent that the entire blower housing structure together with the motor 94 and the blowers 102 and 103 can be removed as a unit from the casing 39 merely by removing screws 123 55 which hold the arcuate upper section of the casing 39 in position, then removing the screws 78 supporting the frame 79 and finally removing the structure through the opening formed by the removal of the section 68.

From the blower outlets 91 and 92, the air is 60 discharged downwardly along the front wall 69 of the inner casing, and therebeyond is reversed in direction by the semi-cylindrical bottom portion 71 thereof. From this region the air moves upwardly into the outlet region 83 behind the blower housing assembly.

In passing through the casing 39 and the highly atomized conical-shaped liquid spray bursting from the peripheral portion of the film 56, the air 70 passes downwardly through that space forwardly of the spray nozzle 42 and along the front wall of casing 39 where it enters the conical-shaped spray by traversing the side thereof, thereafter being reversed in its direction of flow by the curved 75

bottom portion of the casing 39 to flow upwardly through that space rearwardly of spray nozzle 42 and along the rear wall of casing 39 where it passes through the side of the spray and upwardly into the region 83. As a result of its passage through the spray, the air becomes more or less thoroughly mixed with and partially saturated by the spray, and both soluble dirt and odors and insoluble dirt being removed as a result thereof. The flow of air through the spray tends to distort the shape of the spray as well as to cause a deflection thereof with respect to its axis, but in no event not sufficient to diminish the minimum distance from the target 54 to any portion of the inner walls of the casing where the spray strikes the same.

Beyond the passage 83 the moisture-laden air passes through a moisture eliminator and scrubber 126 for further dirt removal and elimination of whatever free moisture is still remaining in the air and which is returned to the humidifying chamber along the rear cabinet wall 72. This eliminator and scrubber plate is removably supported upon a pair of brackets 127 and 128, the former of which is secured along the edge of the blower compartments 88 and 89 and the upper edge of the rear blower compartment frame 82.

The eliminator and scrubber plate consists of a frame 129 having parallel front and rear walls 30 between which are secured a plurality of reversely curved but substantially parallel separating plates 131 and which remove the excess moisture and dirt from the air by dividing the latter into a plurality of isolated currents subjected to turbulent 35 condition of flow by the curvature of the plates. As a result of this turbulence and the division of the air into currents, the moisture and dirt is thrown out of the currents and upon the walls of the plates from whence the moisture and dirt carried thereby drain into the space below.

As will be observed from Fig. 4, the lower edges of all the plates 131 are inclined rearwardly toward the rear wall 72 in order that the water collecting upon the plates may cling by surface 45 tension to the bottom edges thereof and flow into the humidifying compartment therebeneath along the rear casing wall.

In order to provide for the easy installation and removal of the separator 126, the latter is 50 preferably not secured permanently within the upper part of the casing 39, but is merely supported by resting upon the brackets 127 and 128.

Removably disposed above the opening 73 in the upper part of the casing 39, is an outlet casing 132 having an opening 133 in the rearwardly inclined front surface thereof and around the inner walls of which is secured a quantity of sound absorbing material 134. The casing comprises a rear wall 136, an upper wall 137 and a front 60 wall 138, the latter of which is flanged as is indicated at 139 around the opening 133. The front and rear walls of the casing, indicated at 136 and 138, and also the end walls thereof, are flanged inwardly at the bottom, as is shown at 141, in 65 order to provide means for securing therein rear and front sections 142 and 143 of the sound absorbing material 134. An upper section 144 of this material is secured in the casing against the upper wall 137 and above the edge of the rear 70 section 142, by the upper portion of the opening flange 139.

Secured in the outlet compartment 146 intermediate the aforesaid sound-absorbing walls, is a 75 diagonally disposed section of sound-absorbing material 147 which is held in position within the

compartment between brackets 148 engaging the opposite edges thereof and secured between the two compartment ends.

Disposed around the front, sides and top, although not necessarily around the rear walls of the casing 39, is an outer finishing casing 151 which extends downwardly to the floor along a considerable portion of the distance around the lower edges thereof in order to shield from view the water valves and other mechanisms for controlling the spray 42 and which are arranged as shown beneath the casing 39. The outer casing 151, which also extends around the outlet compartment 146, is provided with an inwardly flanged opening 152 within which is secured a grille 153 15 having any kind of suitably curved sections employed both for the purpose of controlling the direction of the air blast discharged from the outlet compartment 146 within the room and preventing the dropping of large articles through the 20 opening into the casing. At the opposite ends of the outer compartment and adjacent the lower extremity thereof, there is formed a plurality of air inlet openings indicated at 154 and through which air for the blowers 102 and 103 is preferably supplied. The air thus admitted passes upwardly around the surfaces of the inner compartment 39 and thereafter flows to the blowers 102 and 103 through the blower inlets 112.

The passageways formed between wall portions 30 of the inner and outer casings may be provided with air filters or strainers 201 for precipitating the oily, sticky dirt commonly entrained in air. In Figs. 14 and 15 there is illustrated a form of sound-absorbing box and filter which may be 35 disposed between the walls of the inner and outer casings to provide air inlets for the device.

The sound-absorbing box 202 may be of rectangular form and constructed of slabs of acoustical material and provided with a low resistance filter 201 of relatively large surface area for screening the air as it passes from the inlet provided by the open end of the box to the opening 203 adjacent the opposite end thereof and which coincides with air inlet openings 112. This 45 filter removes from the air, as the same is passed therethrough, the sooty, sticky dirt usually contained in air and the particles of which are relatively fine and which otherwise would accumulate on the internal walls and parts of the apparatus to reduce the efficiency thereof as well as to necessitate periodic cleaning of the apparatus.

In order to prevent the generation and transmission of sound by the walls of the inner compartment 39, it is preferable to cover a greater 55 portion thereof with some adhesive substance and then to apply thereto a thin sheet of felt or other sound absorbing material indicated at 135. The end walls of the outer casing also should be spaced a considerable distance from the end walls 60 of the inner casing in order to provide air inlet passages 157 for permitting the unobstructed flow of air from the inlet openings 154 in the outer casing to the inlets 112 for the blowers 102 and 103.

In the inlet passages 157, in lieu of the sound-absorbing box 202, sections 158 of any suitable sound-absorbing material such as felt, and which may be secured against the inner surfaces of the end walls of the outer casing by removable brackets such as are indicated at 159 and 161 may be employed. The brackets 159, which hold the front edges of the section 158 in position (see Fig. 3), consist of elongated pieces of sheet metal having bent ends indicated at 162 which are 70 75 80 85 90 95

- adapted resiliently to engage the edges of the sound absorbing material sections. These brackets can be merely placed in position along the front wall of the outer compartment, and due to the resiliency of the sound absorbing material which the ends 162 engage, the brackets will be held in position without further effort. The brackets 161, securing in position the rear edges of the sections 158, also have bent ends, as is indicated at 164, which are likewise adapted to engage the edges of the sections 158 and are separately secured in position inside of flanges 166 formed on the rear edges of the outer compartment end walls.
- 15 As is indicated by Fig. 11, the outlet compartment 132 may be provided with sound-absorbing material elements such as those indicated at 167, 168, 169, 171, and 172, the first of which is disposed horizontally within the front portion of 20 the opening 73 and immediately adjacent the opening 133, while the latter is secured against the upper wall of the compartment. The intermediate sections 168, 169, and 171 each comprise horizontal and vertical sections indicated at 173 25 and 174, respectively, and which are arranged in parallel relation between the openings 73 and 133 in such manner as to divide the space within the compartment 132 into a plurality of parallel outlet passages 176.
- 30 The aforesaid sections of sound-absorbing material may be held in position in any suitable manner as, for example, by brackets 177 secured against the end walls of the compartment 132.
- As is shown by Fig. 12, the heated water for 35 the apparatus may be supplied by a heater such as that indicated at 178 which, in the present instance, comprises an outer jacket 179, surrounding a hot water or other pipe 181 having heat radiating fins 195, and having gaskets 182 40 at the opposite ends which are tightly clamped between the jacket and the pipe by clamps indicated at 183. The jacket is provided with a suitable inlet, shown at 184, and an outlet to the apparatus connected to the hot water pipe 23.
- 45 It is to be understood, of course, that these heaters are shown merely for the purpose of illustrating heat exchange apparatus generally, in as much as it is generally known that the temperature of the feed water for water spray such as is illustrated in the apparatus herein disclosed, may be varied for increasing or decreasing the temperature and humidity of room air.
- It will be observed that the lower part of the 50 ends of the outer casing 161 are curved outwardly away from the building wall, as is indicated at 186, to provide spaces for accommodating a wall base board indicated at 187 and which is generally employed around the walls of rooms adjacent the floor. Adjacent the bottom of the base 55 board, the ends of the casing are further relieved, as at 188 for the purpose of providing spaces for accommodating a molding 189 such as is generally employed in combination with the base board illustrated at 187.
- 60 For the purpose of carrying away the water which collects within the bottom of the casing 39, and which is not absorbed by the air passing through the spray 62, there is provided a drain pipe indicated at 191 which is secured to the casing 39 in communication with an opening 192 formed therein by a coupling member 193. When installing the apparatus, this drain pipe is projected through an opening cut in the room floor and from whence it is extended to communicate 65 with any waste water disposal pipe with which
- the building in which the apparatus is installed may be provided. The only other installation work required for the operation of the apparatus is the connection of the water supply pipes 22 and 23 (if water at different temperatures is to be employed) and the installation of whatever heat exchange apparatus may be considered desirable. Thereafter the apparatus may be put into operation merely by connecting the plug 19 for supplying electrical energy to the motor 94. 10
- The amount of moisture supplied to a room may be controlled throughout considerably wide limits merely by controlling the temperature of the water supplied thereto or by changing the feed water pressure, or both. If the moisture content 15 of the room is to be controlled by the temperature of the water supplied thereto, the valve 28 may be adjusted in such manner as to supply water of the desired temperature through the conduit 29 (provided such valve is employed in 20 the apparatus) or if the moisture content of the air is to be controlled by the spray feed water pressure, then this may be varied merely by properly adjusting the control knob 36 with which the pressure regulating valve 34 is provided, as 25 the amount of moisture absorbed by the air normally will vary, with a variation in the pressure of the water supplied to the nozzle.
- While the structures and methods disclosed herein may be considered as illustrating a preferred form and application of the principles of invention, there is no intention to limit the invention to anything less than is fairly to be considered within the scope of the appended claims. 30
- What is claimed is:—
1. An air conditioning apparatus comprising a casing adapted for the circulation of air internally thereof, a blower compartment arranged in said casing and having blower outlets therein for directing a blast of air within the casing in a predetermined direction, means for discharging finely divided liquid particles into said blast of air within said casing, said blower outlets having inclined drain means arranged along the lower edges thereof, for draining moisture, collecting 45 upon the surfaces of said blower outlets, toward the inside walls of said casing.
2. An air conditioning apparatus comprising a casing adapted for the circulation of air internally thereof, blower means within said casing for circulating the air therein in a predetermined direction, spray means for supplying finely divided liquid particles to said air blast, and drain means associated with said spray means for conducting the water collecting upon the surfaces 50 thereof toward the walls of said casing.
3. An air conditioning apparatus comprising a casing adapted for the circulation of air therethrough, means within said casing for moving a current of air inwardly of said casing and outwardly therefrom, means within said casing for supplying finely divided liquid particles to said air current, and means associated with said air moving means and liquid supplying means for carrying the excess moisture collecting thereon 55 toward the interior surfaces of the side walls of said casing.
4. An air conditioning apparatus comprising a casing adapted for the circulation of air therein, said casing having a bottom wall having control 60 apparatus arranged therebeneath, spray means within said casing for operation in response to the operation of said control means and an outer casing surrounding said inner casing, said outer casing having an apron portion extending around 65

the lower extremity of said inner casing for partially shielding said control means from view.

5. In an air conditioning apparatus, the combination of an inner casing adapted for the circulation of air therein with a separable outer casing disposed in spaced relation to said inner casing throughout a portion of its inner surface, said inner casing having an air inlet opening in communication with said space between said casings 10 and adapted for the admission of air from said space to said inner casing, said outer casing being provided with an air inlet opening to said space between said casings, a readily removable filter medium in said space between said casings for 15 filtering air prior to its passage through said air inlet opening in said inner casing, outlet openings in said inner and outer casings for discharging air from said inner casing, and air conditioning means within said inner casing for drawing air 20 into said inner casing through said inlet openings and said space between said casings; conditioning said air and discharging the same from said inner casing through said outlet openings.

6. In a room or similar relatively small enclosure air conditioning unit, a portable apparatus comprising a container in combination with a separable, structurally independent casing for partially enclosing the same, a passageway formed between portions of the walls of said container and casing and in communication with the atmosphere about the bottom of said unit, an opening in said container in communication with said passageway, communicating outlet openings in said container and casing for directing air 35 discharged from said unit into the regions of said room above said unit, air conditioning means within said container for drawing room air through said passageway and opening; conditioning said air; and discharging the same 40 through said outlet openings into the regions of said room above said unit, and control means for said air conditioning means disposed externally of said container and concealed by said casing.

7. Air conditioning apparatus comprising a 45 casing adapted to house mechanism for circulating and conditioning air, a pair of elongated boxes having walls of sound absorbing material externally secured to said casing at the sides thereof, said boxes providing air inlet passageways to said casing, a housing internally provided with slabs of sound absorbing material and secured to said casing at the top thereof, said housing providing an air outlet passageway from said casing, and a cabinet structurally independent of said casing and adapted for enclosing said casing, said boxes and said housing.

8. Air conditioning apparatus comprising an integral casing open at the top thereof, a frame secured within said casing adjacent the upper 60 end thereof and having a back portion spaced from the walls of said casing to define a passage between said back portion and one of the walls of said casing and a blower compartment between said back portion and an opposite wall of said 65 casing, blower mechanism disposed within said compartment and adapted for discharging air downwardly therefrom into said casing, separator means disposed within said passage, a housing secured to said casing above said separator 70 means and providing an outlet compartment, said housing being internally provided with slabs of sound-absorbing material about the opening therefrom, and a cabinet structurally independent of said casing and adapted for enveloping 75 the same, said cabinet being provided with a

grilled opening registering with the opening in said housing.

9. In a unit air conditioning apparatus, the combination of a casing having an inlet and an outlet at the upper end thereof, means for creating a spray formation within the lower portion of said casing, means within said casing for drawing air through said inlet opening and effecting a flow of air through said spray formation, and thence out of said casing through said outlet opening, an elongated compartment disposed on one side of said casing and the internal walls of which are of a rough fibrous material and having an opening in the upper end thereof coinciding with said inlet opening through 15 said casing, and a second opening disposed at an elevation lower than said first opening and in communication with atmosphere about the bottom of said casing, an air filter secured in said compartment having a low resistance to the 20 flow of air therethrough and a surface area greater than the cross sectional area of the air passageway formed by said compartment.

10. In an air conditioning unit, a casing affording a spray chamber through which air 25 is adapted to be passed and having an opening at the upper end thereof for the discharge of air therefrom, with means within said spray chamber for creating a spray formation therein, and an outlet chamber in communication with said 30 outlet opening and comprising a plurality of tortuous passageways formed between a plurality of sheets of sound-absorbing material spaced from each other by strips secured between said sheets along the side edges thereof.

11. In an air conditioning unit, a casing providing a spray chamber through which air is adapted to be passed and having an opening through which air is discharged therefrom, with means within said spray chamber for creating 40 a spray formation therein, and a sound-absorbing box through which said discharged air is passed, in communication with said opening and comprising a hood having a reduced opening for increasing the velocity of the discharged air and 45 a plurality of tortuous passageways formed between spaced slabs of sound-absorbing material disposed within said hood and effective for deadening the noises attending the formation of said spray and the passage of air therethrough.

12. In an air conditioning unit, a casing through which air is adapted to be passed for conditioning the same and having inlet and outlet openings at the upper end thereof, a vertical wall dividing the upper portion of said casing, 55 brackets affixed to said wall and to the walls of said casing, a horizontal wall supported upon said brackets and having openings therein, a blower disposed within the compartment formed by said walls and upon said horizontal wall, and 60 adapted to draw air through said inlet openings and discharge the same downwardly into said casing through the openings in said horizontal wall, and a cover plate for closing said compartment.

13. In an air conditioning unit, a casing through which air is adapted to be passed for conditioning the same and having an outlet opening at the top thereof and inlet openings at the side adjacent the upper end thereof, a vertical 70 wall dividing the upper portion of said casing, brackets fixed to said wall and to the walls of said casing, a horizontal wall supported upon said brackets and having openings therein, a blower disposed within the compartment formed 75

by said horizontal and vertical walls and portions of the casing walls and upon said horizontal wall, and an excess moisture eliminator disposed in said casing on the opposite side of said vertical wall to said blower, means for creating a spray formation within said casing and below said horizontal wall, said blower being adapted to draw air through said inlet openings and discharge the same downwardly into said 10 casing through the spray formation and thence upwardly through said excess moisture eliminator, and a cover plate for closing the compartment in which said blower is disposed.

14. In an air conditioning unit, a casing providing a spray chamber through which air is adapted to be passed and having openings through which air is taken therein and discharged therefrom, respectively, with means within said spray chamber for creating a spray

formation therein, a sound-absorbing box through which the discharged air is passed in communication with one of the openings and comprising a hood having a plurality of tortuous passageways formed by spaced slabs of 5 sound-absorbing material disposed therewithin, and a chamber the walls of which are covered with sound-absorbing material through which the intake air passes before entry thereof into said casing, said hood and chamber being effective for deadening the noises attending formation of the spray and the passage of air therethrough, an excess moisture eliminator disposed within said casing adjacent the outlet opening, and a removable filter disposed within said 15 sound-absorbing chamber adjacent the inlet opening to said casing.
